TREATMENT OF MOTOR FUEL

Friedrich W. Leffer, Kenton-Harrow, England,
assignor to Universal Oil Products Company,
Chicago, Ill., a corporation of Delaware

Application November 30, 1938, Serial No. 243,173

5 Claims. (Cl. 196—50)

This invention relates more particularly to the treatment of motor fuels of gasoline boiling range and still more particularly to such gasolines of highly paraffinic characteristics which, as is well-known, ordinarily possess inferior knock ratings.

The invention is more specifically concerned with a combination of steps involving fractionation, cracking, and polymerization of olefins produced in the cracking to convert the gasoline charged into high yields of improved antiknock value material with a minimum of losses.

It is current practice to "reform" low antiknock value gasolines whether these are produced directly from primary distillation of crude petroleums or from cracking operations on heavier cuts which have not produced the desired antiknock rating in one operation. The utility of reforming processes is limited by the character of the gasoline to be reformed and the increase in knock rating desired and the process is frequently uneconomical when attempts are made to increase the antiknock value of a highly paraffinic gasoline to a point enabling it to be sold as premium motor fuel, since a balance must be struck between the increased value of the product and the rapidly mounting losses after a certain antiknock value is exceeded. The present process is a contribution to the art of raising the antiknock value of paraffinic gasolines to some optimum value commensurate with the economics of any situation.

In one specific embodiment the present invention comprises fractionating a low antiknock value gasoline into light and heavy fractions, separately cracking the light and heavy fractions in coil and chamber systems, fractionating the products of cracking the light fraction into fixed gases and light vapors containing relatively high percentages of polymerizable olefins, fractionating the products of cracking the heavy fraction into fixed gases, gasoline boiling range materials, and stocks heavier than gasoline, combining the gaseous products from the two cracking operations, polymerizing the combined gases to form gasoline boiling range hydrocarbon fractions, blending these fractions with the gasoline boiling range products from cracking and stabilizing the blend to a marketable vapor pressure.

The process thus briefly outlined is capable of considerable modification without departing from the scope of the invention, but for the sake of illustrating a characteristic operation the attached drawing has been provided to permit a description of its essential steps. The drawing

shows interconnected units of conventional form in general side elevation and is not drawn to any absolute or relative scale.

Referring to the drawing, low antiknock value gasolines such as, for example, those from the Pennsylvania or Michigan fields or from processes involving the synthesis of hydrocarbons by the interaction of carbon monoxide and hydrogen are introduced to the plant by way of line 1 containing valve 2 and taken by a charging pump 3 which discharges by way of lines 4 and 5 containing valve 6 into a primary fractionator 20. Although not a special feature of the invention, provision may be made for adding sufficient heat to the incoming charge to insure its proper fractionation by diverting portions through indirect heat exchangers receiving heat from the products of the two cracking units. Thus valve 10 in line 4 leads through heat exchanger 11 which receives cracked products from the light oil cracking unit and the preheated charge passes through line 12 containing valve 13 back to line 5. Similarly line 14 containing valve 15 leads to heat exchanger 16 on the line of the products from the cracking of the heavy fraction of the gasoline and line 18 containing valve 19 permits the return of the portion of the charge thus diverted back to line 5. In lieu of the heat exchangers shown conventional tubular heating units may be employed.

The preheated charge may be passed through valve 7 in line 5 at approximately the middle level of the fractionator 20 or through line 8 containing valve 9 representing any other branch line which may be employed to introduce the charge at some other level. Fractionator 20 may be operated at a moderately superatmospheric pressure of the order of 100-150 lbs. per square inch and is indicated as having a cooling coil 21 for assisting fractionation although any suitable type of fractionator may be used. As a rule gasolines are fractionated into approximately equal volumes although this may be varied in any direction in the case of different charging stocks to take advantage of special characteristics of the light and heavy fractions which permit their separate treatment under conditions conducive to the best overall results.

Vapors from fractionator 20 pass through line 22 containing valve 23 and are preferably condensed to permit easier pumping up to the required pressures for the reforming operation, these pressures being normally of the order of 1000-1500 lbs. per square inch although any superatmospheric pressure may be used which

proves advantageous. The vapors pass through a condenser 20' and accumulate in receiver 21' from whence they are taken by way of line 22' containing valve 23' to a pump 24' which is of a design and capacity for developing the required pressure, the overhead distillate being pumped through line 25' containing valve 26' to pass through a heating element 24 contained in a cracking furnace 25. The temperatures commonly employed in cracking the lighter fractions are of the order of from 1000 to 1050° F. although this temperature will obviously be varied with the chemical character and boiling range characteristics of the stock cracked. Likewise element 24 is merely representative of any type of heater which may be employed to raise the temperature of the inlet material to a point which will insure its proper conversion. In the interests of simplicity in showing the general flow of the process, reaction chambers have been omitted following the cracking coils although these may be used if found desirable and in the case of the light fractions undergoing discussion, the cracked products pass through line 26 and through heat exchanger 11 already mentioned and thence through valve 27 to a fractionator 28 whose function is to separate out as a light overhead all of the fractions which can be profitably polymerized to make high antiknock boiling range material while the heavier portions are returned for blending with similar products from the cracking of the heavy fraction and the products of polymerization. Fractionator 28 has a draw line 29 containing valve 30 and leaving the cooler 31 which may be operated to exert a variable cooling influence on the fractionator bottoms so that a portion may be taken by pump 32 and discharged by way of line 33 containing valve 34 back to line 26 and thence into the fractionator to control the temperature of the inlet vapors and assist the fractionation operation. A major portion of the tower bottoms is however discharged through line 35 containing valve 36 to line 65 to be presently described and blended with the products of the cracking of the heavier fraction.

Vapors from fractionator 28 may follow line 37 containing valves 38 and 39 and pass directly to the polymerizing unit comprising chambers 49 and 52. For careful control of the overhead, however, it is best practice to condense it and operate with valve 38 closed, the vapors passing through line 40 into condenser 41 and the liquefied portions following line 42 containing valve 43 to intermediate receiver 44 from whence fixed gases may be returned to line 37 by way of line 49' containing valve 50'. The condensate may be then returned to the top of the fractionator by way of line 45 containing valve 46 to pump 46' to line 47 containing valve 48. The element shown permits a very definite control of the composition of the material leaving the top of the fractionator. According to the present process the light vapors and fixed gases from the fractionating operation just described along with the fixed gases from the heavy fraction cracking operation to be presently described are subjected to polymerization treatment preferably in the presence of catalysts to produce gasoline boiling range materials for blending with the normally liquid gasoline boiling range cracked products. Chambers 49 and 52 connected in series by line 50 and valve 51 are shown to represent any arrangement of chambers containing catalysts which may be employed. While the process is not limited to any particular type of catalyst a convenient and satisfactory

material consists of the so-called solid phosphoric acid catalyst which is produced by the general steps of forming a paste of the phosphoric acid and a relatively inert finely divided siliceous material such as kieselguhr, calcining the paste at temperatures up to about 400° C. to produce a solid cake, grinding and sizing the cake to produce particles of approximately 6 to 20 mesh and rehydrating the acid constituent of the particles by contact with steam at approximately 500° F. to produce a catalytic acid of optimum composition. This procedure may be varied by forming particles from the original paste by pelleting or extrusion methods and then calcining the particles after which steaming is resorted to. These catalysts are highly effective in polymerizing low boiling point olefins to produce high yields of dimers and trimers thereof which have high antiknock value and which according to the present process are blended with the other cracked fractions of gasoline boiling range to produce a product of high antiknock value. These catalysts are easily reactivated after having been rendered inactive on account of carbon deposition over a period of time by the simple steps of burning off the carbonaceous deposits with low oxygen-content gas mixtures such as flue gas and then steaming as in their manufacture.

The temperatures and pressures employed in the polymerizing operation depend upon the composition of the materials charged at this point. When the charge to the polymerizing chambers comprises principally hydrocarbons of from 2 to 5 carbon atoms and thus the olefins, ethylene, propylene, butylenes, and amylenes, the temperatures employed may be varied from approximately 350-550° F. while employing pressures of the order of 100-500 lbs. per square inch. Conditions of temperatures, pressures, and times of contact are preferably chosen so that there is a minimum production of hydrocarbon liquids boiling above the end-point of gasoline.

Returning to the primary fraction of gasoline charged to the plant the heavier fraction thereof passes through line 58 containing valve 59 to a pump 60 which discharges through line 61 containing valve 62 to a heating element 63 arranged to receive heat from a furnace setting 64. As stated in connection with the light fraction cracking furnace, the drawing merely represents any type of cracking element including a coil and reaction chamber which may be employed and the invention is not limited to the specific furnace element shown. The conditions employed in cracking the heavy ends of gasolines will again vary with the boiling range of the fractions treated and their chemical characteristics although in general relatively high pressures of the order of 700-1200 lbs. per square inch are most suitable while temperatures are generally somewhat lower than those used on the light fractions although these temperature ranges may at times overlap.

The cracked products from heating element 63 pass through line 65 through heat exchanger 16 already mentioned and thence through valve 65' to fractionator 66 which functions to remove all materials heavier than gasoline as a bottom reflux while passing overhead all fixed gases and material of gasoline boiling range. The bottoms from the fractionator pass through line 67 containing valve 68 and thence through a cooler 69 to a pump 70 may discharge any portion of heavy residual material through line 71 containing valve 72 or return a portion thereof to line 65 by

way of line 73 containing valve 74 to assist in regulating the temperature of the material entering the fractionator. Heavy gasoline boiling range material from fractionator 28 enters line 65 by way of line 35 containing valve 36.

The overhead from fractionator 66 passes through line 75 containing valve 76 to condenser 77 and the liquefied components plus fixed gases follow line 78 containing valve 79 to receiver 80 from whence the gases are released through line 81 containing valve 82 to undergo polymerization with the gaseous and light liquid products from the cracking of the light fraction. In order to control the temperature of the gases entering the polymerizing unit, they are passed through line 84 containing valve 85 to a tubular heating element 86 arranged in a furnace 87 and thence by way of line 88 containing valve 89 back into line 81, valve 83 being closed.

The gasoline boiling range material accumulating in receiver 80 is lead through line 90 containing valve 91 to a pump 92 which discharges a portion of the condensate through line 93 containing valve 94 back to the top of fractionator 66 to control the composition of the vapors leaving the fractionator and the remainder of the liquid products pass through valve 95 in line 95 to the stabilizing operation. The total polymer products pass through line 53 containing valve 54 although as a matter of temperature control, a portion of the polymers may be diverted through line 55 containing valve 56 through cooler 51, since the temperature required for stabilization is ordinarily much lower than that of the polymer products. However, since the products from receiver 80 are at normal atmospheric temperature, it is intended to utilize the heat of the polymer products to raise the total material entering the stabilizer to a point necessary for the proper functioning thereof.

The total products of approximate gasoline boiling range in both cracking operations and the polymerization unit pass through heat exchanger 96 to pick up heat from the bottoms of the stabilizer and then follow line 97 which has branch lines 98 containing valve 99, line 100 containing valve 101, and line 102 containing valve 103, which permit the admission of the products to be stabilized at different levels in the stabilizer. The function of the stabilizer is substantially the same as any other stabilizer in cracking or refining operations, sufficient amount of dissolved and normally gaseous constituents comprising principally 2, 3, and 4 carbon atom hydrocarbons being released to lower the vapor pressure to approximately 10 lbs. per square inch although this is currently varied from summer to winter to from 8 to 12 lbs. respectively. The overhead stabilizer vapors pass to line 104 containing valve 105 through a condenser 106 and thence through a rundown line 107 containing valve 108 to a stabilizer reflux receiver 109 which has a gas release line 110 containing valve 111 and a liquid recirculating line 112 containing valve 113, the condensate being taken by pump 114 and discharged back into the top of the stabilizer by way of line 115 containing valve 116 to assist in controlling the boiling point of the emergent vapors.

The bottoms from the stabilizer constituting the desired product of the process follow line 117 containing valve 118 through heat exchanger 96 already mentioned and thence through line 119 containing valve 120 to cooler 121 having

draw line 122 containing valve 123 leading to storage.

The following example is included to illustrate the character of the results obtainable in the application of the above described process to the commercial problem of reforming gasolines although not with the intent of correspondingly limiting the generally broad scope of the invention.

A straight run gasoline of a highly paraffinic character produced in the primary fractionation of a Pennsylvania crude oil was refractionated into approximately equal light and heavy fractions. The lighter fraction was cracked at a temperature of 1030° F. under a pressure of 1200 lbs. per square inch and subsequently separated into an overhead fraction containing all of the three and four carbon atom hydrocarbons produced in the cracking operation and a bottoms of low vapor pressure of the order of 2-3 lbs. per square inch by the Reid method of testing. The heavier end of the gasoline was separately cracked at a temperature of 1020° F. and a pressure of 1000 lbs. per square inch and fractionated along with the low vapor pressure material from the cracking and fractionation of the primary light fraction to produce a liquid overhead of motor fuel boiling range and heavier bottoms boiling above 425° F. which were rejected from the process.

The total overhead gaseous products from the fractionation of the products of cracking the light end of the gasoline and the total gases separated from the overhead gasoline from the fractionator operating upon the products from cracking the heavy end of the gasoline were contacted with granular solid phosphoric acid catalysts at temperatures within the range of 350-450° F. under a pressure of approximately 300 lbs. per square inch and the total products cooled and added to the stream of motor fuel boiling range products from the final cracking plant fractionator. The total blend of the materials was then stabilized to a vapor pressure of 10 lbs. per square inch and it was found that the total overall yield of stabilized product was 90% of the original gasoline fractionated. The octane number was raised from 40 to 70 by the method of processing and the product was therefore suitable for marketing as premium motor fuel, both in respect to boiling range, vapor pressure, and octane number.

I claim as my invention:

1. A process for producing anti-knock motor fuel from gasoline distillates of low anti-knock value which comprises separating the distillate into a light fraction and a heavier fraction, cracking said light fraction in a heating zone and separating from the resultant products a condensate containing heavy gasoline hydrocarbons and a lighter fraction containing normally gaseous olefins, reforming said heavier fraction of the distillate in a second heating zone, commingling at least a portion of said condensate with the heated products from the second heating zone, fractionating the resultant mixture to separate a gasoline product from normally gaseous olefins, combining the latter with said lighter fraction containing normally gaseous olefins, subjecting the thus commingled materials to polymerization, and recovering gasoline boiling hydrocarbons from the products of the polymerization.

2. A process for producing anti-knock motor fuel from gasoline distillates of low anti-knock

value which comprises separating the distillate into a light fraction and a heavier fraction, cracking said light fraction in a heating zone and separating from the resultant products a condensate containing heavy gasoline hydrocarbons and a lighter fraction containing normally gaseous olefins, reforming said heavier fraction of the distillate in a second heating zone, commingling at least a portion of said condensate with the heated products from the second heating zone, fractionating the resultant mixture to separate a gasoline product from normally gaseous olefins, combining the latter with said lighter fraction containing normally gaseous olefins, subjecting the thus commingled materials to polymerization, combining resultant polymerization products with said gasoline product and stabilizing the mixture to the vapor pressure of motor fuel.

3. The process as defined in claim 1 further characterized in that a second portion of said condensate is commingled with the effluent of the first-mentioned heating zone.

4. A process for producing anti-knock motor fuel from gasoline distillates of low anti-knock value which comprises separating the distillate into a light fraction and a heavier fraction, cracking said light fraction in a heating zone and separating from the resultant products a condensate containing heavy gasoline hydrocarbons and a mixture of normally gaseous and normally liquid olefins, reforming said heavier fraction of the distillate in a second heating

zone, commingling at least a portion of said condensate with the heated products from the second heating zone, fractionating the resultant mixture to separate a gasoline product from normally gaseous olefins, combining the latter with said mixture of normally gaseous and liquid olefins, subjecting the thus commingled materials to polymerization, and recovering gasoline boiling hydrocarbons from the products of the polymerization.

5. A process for producing anti-knock motor fuel from gasoline distillates of low anti-knock value which comprises separating the distillate into a light fraction and a heavier fraction, cracking said light fraction in a heating zone and separating from the resultant products a condensate containing heavy gasoline hydrocarbons and a mixture of normally gaseous and normally liquid olefins, reforming said heavier fraction of the distillate in a second heating zone, commingling at least a portion of said condensate with the heated products from the second heating zone, fractionating the resultant mixture to separate a gasoline product from normally gaseous olefins, combining the latter with said mixture of normally gaseous and liquid olefins, subjecting the thus commingled materials to polymerization, combining resultant polymerization products with said gasoline product and stabilizing the mixture to the vapor pressure of motor fuel.

FRIEDRICH W. LEFFER.
